DESIGN FOR A GLASS BOTTLE

Lawrence J. Kihn, Pittsburgh, Pa., assignor to J. T. & A. Hamilton Company, a corporation of Pennsylvania

Application December 14, 1939, Serial No. 88,879

Term of patent 7 years

To whom it may concern:

Be it known that I, Lawrence J. Kihn, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part thereof.

In the drawing: Fig. I is an elevational view of a glass bottle showing my new design; and Fig.
II is a plan view of the said glass bottle.

I claim:

The ornamental design for a glass bottle, substantially as shown.
